(57) **CLAIM**

The ornamental design for low waist rain pants, as shown and described.

DESCRIPTION

FIG. 1 is a perspective view of the low waist rain pants of my new design.

FIG. 2. Is a front elevational view thereof.

FIG. 3 is a back elevational view thereof.

FIG. 4 is a right side elevational view thereof.

FIG. 5 is a left side elevational view thereof.

FIG. 6 is a bottom plan view thereof; and,

FIG. 7 is a top plan view thereof.

The dots within the disclosure represent surface stippling and form no part of the claimed design.
